RADIATOR

James D. Auman, Nazareth, Pa.

Application September 28, 1931, Serial No. 565,658
Renewed September 16, 1933

1 Claim. (Cl. 257—140)

The present invention relates to improvements in radiators for steam and hot water heating systems.

One of the important objects of the present invention is to provide a sectional radiator wherein each section or unit comprises a pair of pressed or stamped out plates constructed of corrosion resisting material, said plates being disposed in interfitting relation with the interfitting edge portions welded.

Another important object of the invention is to provide a radiator construction of the above mentioned character that includes a simple and efficient coupling between the adjacent sections or units.

A still further and important object is to provide a radiator construction of the above mentioned character wherein the parts are so arranged as to afford a free circulation of air around the coils as well as around the couplings connecting the adjacent sections together, thus offering a greater resistance to the separation of the joined parts, thereby preventing leakage.

A further object resides in the provision of a radiator of the above mentioned character which is simple in construction, inexpensive, strong and durable and further well adapted to the purposes for which it is designed.

Other objects and advantages of the present invention will become apparent when taken in connection with the accompanying drawing:

In the accompanying drawing forming a part of this specification, and in which like numerals designate corresponding parts throughout the several views:

Figure 1 is a side elevation of the sectional radiator embodying my invention;

Figure 2 is an end elevation thereof;

Figure 3 is an enlarged detail sectional view illustrating the connection between the adjacent sections; and

Figure 4 is a transverse section through one of the coils showing the interfitting relation between the plates.

In the drawing, wherein for the purpose of illustration is shown the preferred embodiment of my invention, the numeral 1 designates generally my improved radiator, the same comprising a plurality of sections or units, each of which is of the same construction and, therefore, the description of one section or unit will suffice for the description of all.

Each section or unit is formed of a non-corrosive material preferably "Armco" iron which is 55 a very pure grade of wrought iron and which will

resist corrosion better than steel. Other materials such as alloys of aluminum and chrome alloys which are of a corrosion resisting nature may also be employed. Each section is formed of two plates designated by the numerals 2 and 3 respectively which are pressed to the desired shape whereby to form a plurality of spaced coils.

The plate 3 is slightly smaller than the complementary plate 2 so that these plates will have interfitting relation as shown very clearly in Figures 3 and 4 of the drawing. The plates are welded together as at 4, thereby providing a group of passages for the steam or hot water that flows through the radiator connected with the heating system.

Before welding the complementary plates of each section together, the inner surfaces of these plates are coated with lampblack, the purpose thereof being to increase the absorptivity and therefore, the emissivity of the radiator.

The sections of the radiator are connected together through the medium of suitable couplings designated generally by the numeral 5, a pair of such couplings being associated with the upper and lower end portions of each pair of sections or units as clearly disclosed in the drawing. The coupling includes opposed and aligned nipples 6 and 7 that are formed integrally with the opposed sides of the adjacent sections, it being understood of course, that the plates comprising the sections are formed with openings around which these nipples extend.

The nipples are externally threaded as indicated at 9 for the reception of the connecting sleeve 8 which is internally threaded and this construction is more clearly disclosed in Figure 3 of the drawing.

The endmost sections of the radiator may be provided with suitable supporting legs 10 and the radiator when assembled is adapted to be connected with the heating system in the conventional manner.

The provision of a sectional radiator constructed in the manner disclosed and described, renders the same more efficient in its operation and the radiators now generally in use and furthermore, a radiator of the character embodied in the present invention can be manufactured at a much lower cost, both in time and labor than the ordinary radiator.

While I have shown the preferred embodiment of the invention, it is to be understood that various changes in the size, shape and arrangement of parts may be resorted to without departing

from the spirit of the invention and the scope of the appended claim.

Having thus described the invention, what I claim is:

5 In a radiator, a series of sections of corrosion resisting material each section comprising a pair of plates arranged in opposed relation and having interfitting engagement with each other, said

interfitting plates being welded together, a pair of opposed nipples associated with the adjacent sections, said sections being formed with openings around which the nipples extend, and sleeve-like couplings connecting the opposed nipples for affording communication between the several sections. 80

JAMES D. AUMAN.
